UNITED STATES PATENT OFFICE.

FRANCIS KLINE, OF CHICAGO, ILLINOIS, ASSIGNOR OF ONE-HALF TO FRANK BURKMAN,
OF CHICAGO, ILLINOIS.

NEEDLE-THREADER FOR SEWING-MACHINES.

1,235,532.

Specification of Letters Patent. Patented July 31, 1917.

Application filed April 5, 1917. Serial No. 159,845.

To all whom it may concern:

Be it known that I, FRANCIS KLINE, a subject of the King of Great Britain, and a resident of Chicago, in the county of Cook 5 and State of Illinois, have invented certain new and useful Improvements in Needle-Threaders for Sewing-Machines, of which the following is a specification.

This invention relates to improvements 10 in a needle threading attachment for sewing machines, and it consists in certain peculiarities of the construction, novel arrangement and operation of the various parts thereof, as will be hereinafter more 15 fully set forth and specifically claimed.

The principal object of the invention is to provide a device which shall be simple and inexpensive in construction and which can be attached to any kind of a sewing machine 20 in such a manner that when it is desired to thread the needle thereof, the attachment can be turned down or to such a position as to bring the needle guide members in alignment with the eye of the needle, to the end 25 that a thread may be readily passed through said guide members and the eye of the needle. A further object of the invention is to so construct the device that it will automatically release the thread and raise itself 30 to a position to be out of the way in the operation of the machine.

Other objects and advantages of the invention, will be disclosed in the subjoined description and explanation.

35 In the accompanying drawing which serves to illustrate an embodiment of the invention,

Figure 1, is a view looking from the operator's side of a sewing machine, showing 40 a portion of the head of the machine, a part of the bed or throat plate and illustrating by full lines, the attachment secured to the presser-foot-bar and in position with respect to the needle for guiding a thread 45 through the eye thereof, and by dotted lines about the position the attachment will occupy when not in use for threading.

Fig. 2, is an end view showing a part of the head of the sewing machine with the 50 attachment mounted on the presser-foot-bar and the parts in position ready for guiding the thread through the eye of the needle.

Fig. 3, is a cross-sectional view taken on line 3-3 of Fig. 2, looking in the direction 55 indicated by the arrows.

Fig. 4, is a vertical sectional view taken on line 4-4 of Fig. 1, looking in the direction indicated by the arrows, and

Fig. 5, is an end view of a portion of the head of the sewing machine, showing modified means for mounting the attachment on the machine.

Like numerals of reference, refer to corresponding parts throughout the different views of the drawing.

The reference numeral 10 designates a portion of the head of a sewing machine, or that part thereof which carries the needle bar 11 and presser-foot-bar 12, which are mounted on said head for vertical movement

70 in the usual or any well-known way. A needle 13 is secured vertically in the lower end of the needle bar 11 by means of a setscrew 14 which is extended through a collar 15 on the lower end of the bar 11 and is 75 adapted to engage the upper end of the needle which is fitted in a socket in the lower end of the needle bar as usual. The needle is provided near its lower end with an eye or opening for the thread and said 80 opening is disposed longitudinally with respect to the machine. The holder or carrier for the attachment consists of a block 16 which has pivotally mounted thereon at one of its ends a pair of spaced apart clamping 85 jaws 17 which are adapted to embrace the presser-foot-bar 12 at a suitable distance above the presser-foot 18 which is mounted on the lower end of said bar. The jaws or members 17 are connected together by means 90 of a screw bolt and a wing nut 20 on one end of said bolt so that by turning the nut in the proper direction the members 17 will be caused to clamp the bar 12 on which they are mounted. The block or carrier 16 is 95 provided near its outer end, or that end opposite the members 17, with a transverse opening 21 which opening is reduced at one of its ends as at 22 as is clearly shown in Fig. 3 of the drawing. The other end of the 100 opening 21 is internally screw-threaded to engage a screw plug 23 which is adapted to rest against the adjacent end of a rod 24 which is provided at its other end with a reduced portion 25, which extends through the reduced portion 22 of the opening 21 and into an opening 25a located in one end of a rotatable member 26 which extends 105 horizontally from the carrier 16 on one side thereof and near the needle bar, but to the 110

left thereof as shown. A screw 27 seated in the member 26 is employed to engage the reduced portion 25 of the rod 24 and to fix the member 26 on said portion. Surrounding 5 the rod 24 is a spiral spring 28 which has one of its ends secured to the carrier 16 and its other end to the rod 24 and this spring is used to rotate said rod and the member 26 when the latter is unlocked from the 10 holder 16 as will be presently explained. The member 26 is provided centrally and longitudinally thereof with an opening 29 which has its outer end screw-threaded to engage a screw plug 30 the inner end of 15 which rests against a coiled spring 31 contacting with a plunger or locking-bolt 32 which is extended at its end adjacent to the carrier 16 into a recess 33 in the side of said carrier, where said bolt will be held 20 by reason of the tension of the spring 31 until it is released by the movement of an arm 34 on a bell-crank-lever 35 which is fulcrumed to and carried by a depending extension 36 on the member 26 adjacent to 25 the carrier 16. The arm 34 constitutes one of the arms of the lever 35, and extends upwardly into an enlargement 37 of the opening 29 in the member 26 and is adapted to engage the plunger or locking bolt 32 so as 30 to retract the same and withdraw its inner end from the recess 33 in the carrier 16 and thus unlock or release the member 26 from the carrier so that it may be automatically rotated or turned in order to raise the parts 35 of the attachment to about the position shown by dotted lines in Fig. 1 of the drawings, or so as to be out of the way of the operation of the machine. The other arm 38 of the bell-crank-lever 35 is longitudinally slotted and extends longitudinally under and with respect to the member 26, which member has extended downwardly therefrom between the arm 38 and the needle bar 11 a pair of spaced apart resilient rods 40 45 39 each of which has adjustably mounted on its lower end a thread and needle guiding member 40 which projects into the path of the needle 13 as is clearly shown in Fig. 1 of the drawing, and each has an extension 50 41 to embrace the point of the needle just below the eye therein. Each of the members 40 is provided on its inner surface with a semi-circular recess 42 which recesses are tapered toward the ends of the members 40 55 adjacent to the needle 13 and form when said members are in juxtaposition a flared or funnel shaped guide leading at its contracted end to the eye of the needle. The members 40 can be adjusted on the rods 39 by means of setscrews 43 which each of them carries and which are adapted to engage said rods. Just above the members 40 each of the rods 39 is provided with an enlargement 44 each of which has in its upper portion and inner surface a downwardly beveled

recess 45 to receive the tapered or wedge shaped portion 46 on the lower end of a sliding bar 47 which is mounted between the rods 39 and has at its upper portion a laterally projecting pin 48 which engages the slot in the longer arm 38 of the bell-crank-lever 35. This sliding bar 47 is provided with a bayonet slot 49 in which is located a tripping lever 50 which is fulcrumed on the lower end of a projection 51 depending from the member 26 on the opposite side of the lever 35 from that on which the needle bar is located. The free portion of the lever 50 is vertically slotted to receive the needle 13 below the collar 15 on the needle bar 11, 80 and is so located that when the needle is in such position that the eye of the needle carried thereby will communicate with the smaller end of the guide opening for the thread formed by the tapered recesses 42, 85 said collar will rest lightly on the tripping lever 50. When thus positioned a thread may be inserted in the end of the opening formed by the recesses 42 in the guide members 40 and will be guided thereby to and through the eye of the needle, when by a slight downward movement of the needle bar the collar 15 thereon will depress the lever 50 thus forcing the sliding bar 47 downwardly into the beveled recesses 45 95 of the members 44, thus causing said members to be separated and at the same time the guide members 40, thus permitting the thread to be released from the last named members. In the foregoing operation, as 100 the bar 47 is moved downwardly the pin 48 which it carries will depress the longer arm 38 of the lever 35, in which action the arm 34 will force the locking bolt 32 outwardly and thus release the member 26 from the carrier 16, so that the tension of the spring 28 on the rod 24 will cause the member 26 to turn to about the position shown by dotted lines in Fig. 1 of the drawings.

In Fig. 5 of the drawing, is shown a 110 modification in the means for securing the attachment to a sewing machine and which consists in dispensing with the clamping jaws 17, screw 19 and nut 20 and extending a bracket 52 upwardly from the outer portion of the carrier block 16, which bracket is provided with openings 53 to be used for securing it to the face of the machine head.

Having thus fully described my invention, what I claim as new and desire to secure by Letters Patent is—

1. In a needle threader for sewing machines, the combination with a carrier-member having means to secure it to a part of the machine near the needle-bar thereof, of a spring-actuated rotatable member extended from one side of the carrier-member, means depending from the rotatable member to near the point of the machine needle, thread guiding jaws mounted on the said 130

depending means and having a guide-way to communicate with the eye of the needle, and means actuated by the downward movement of the needle-bar to separate said jaws.

- 5 2. In a needle threader for sewing machines, the combination with a carrier-member having means to secure it to a part of the machine near the needle-bar thereof, of a spring-actuated rotatable member extended from one side of the carrier-member, means depending from the rotatable member to near the point of the machine needle, thread guiding jaws mounted on the said depending means and having a guide-way 10 to communicate with the eye of the needle, and means actuated by the downward movement of the needle-bar to separate said jaws to release the thread and to unlock the rotatable member from the carrier-member so 15 as to permit rotation of the rotatable member.

- 20 3. In a needle threader for sewing machines, the combination with a carrier-member having means to adjustably secure it to the presser-foot-bar of the machine, of a spring-actuated rotatable member extended from one side of the carrier-member, a pair of parallel resilient bars or rods depending from the rotatable member to near the point

of the machine needle, a thread guiding jaw 30 mounted on the lower portion of each of said bars or rods each having on its inner surface a correspondingly tapered guide-way communicating with the eye of the needle, a member fixed on each of said bars 35 above said jaws and having in their adjacent upper portions downwardly inclined recesses, a bar mounted for vertical movement between said bars and having its lower portion tapered to enter said recesses, a lever 40 supported by the rotatable member and extended through an opening in said slideable bar and extended into the path of the needle bar, a pin on the upper portion of the slideable bar, a bell-crank-lever fulcrumed on 45 the rotatable member and having one of its arms in loose engagement with the pin and its other arm extended into an opening in the rotatable member and a spring-actuated locking bolt mounted on the rotatable member and tapered to engage the last named arm of said bell-crank-lever, as well as the carrier-arm. 50
